UNITED STATES PATENT OFFICE.

LAWRENCE A. MUELLER, OF KANKAKEE, ILLINOIS.

BASS-DRUM BEATER.

No. 890,161.

Specification of Letters Patent.

Patented June 9, 1908.

Application filed September 28, 1906. Serial No. 336,636.

To all whom it may concern:

Be it known that I, LAWRENCE A. MUELLER, a citizen of the United States, residing at Kankakee, in the county of Kankakee and the State of Illinois, have invented a new and useful Improvement in a Bass-Drum Beater, of which the following is a specification.

This invention relates to a beater for bass drums, combined with a beater for cymbal attached to the drum.

The invention also includes means for holding the drum at rest during the use of the beater.

The invention consists in the novel features of construction hereinafter described, pointed out in the claims and shown in the accompanying drawings in which:—

Figure 1 is a side elevation of the device attached to a drum. Fig. 2 is a front elevation attached to the drum. Fig. 3 is a detail view partly in section showing the means for holding the drum stationary. Fig. 4 is an enlarged view partly in elevation and partly in section showing a portion of the device detached from the drum. Fig. 4^a is a continuation of Fig. 4 showing the beater in section. Fig. 5 is a section on the line 4—4 of Fig. 4. Fig. 6 is a front elevation of the device. Fig. 7 is a plan view of a clamp and sleeve, partly shown in section.

In these drawings A represents a drum having a rim A' to which is attached a clamp B by means of a set screw B'. The clamp is provided with forwardly extending arms B², with a socket B³, and with guides B⁴ projecting in advance of the socket. A vertically arranged sleeve C is held between the arms B² by set screws C' which work through the arms. A beater rod D is adjustably secured in the sleeve by a set screw D' and depends from the sleeve. A spring B⁵ is seated in the socket B³ and bears on one side of the rod D which passes loosely between the guides B⁴.

An upright rod E has its lower end threaded into the upper portion of the sleeve C. The upper end of the rod is angled as at E' and the angled portion passes through a split sleeve E², the sections of the sleeve being locked together by a screw E³. A beater rod E⁴ passes transversely and vertically through the sleeve E² and a thumb nut E⁵ works longitudinally in the sleeve E² and

bears on the rod E⁴. The upper end of this rod carries a cymbal beater E⁶.

The rod D carries a sleeve F which is adjustable along the rod, and locked in position by a set screw F'. On the sleeve is placed a bass drum beater F² of any desired construction. A spring G is connected at one end to the upper end of the rod E, and at the other end to the opposite rim of the drum.

A cymbal H is attached to the drum in the usual manner by a standard H'. To hold the drum steady when in use and resting on the ground or floor I provide slotted sleeves K having base plates K' which are secured to the inner face of the drum rim, and a pin K² works in the sleeve and through the rim, being locked in position by a set screw K³ which works through the slot of the sleeve K. The beater rod is operated by a chain J connected at one end to the lower end of the rod D and at the other end to a foot pedal J', or any other device of the kind, as may best suit the player. The swinging movement of the rod D will be imparted to the sleeve C, rod E and the cymbal rod E⁴, as will be obvious from the drawings and the description of construction.

Having thus described my invention what I desire to claim as new and secure by Letters Patent is:—

1. The combination with a drum rim, a clamp secured thereto, said clamp being provided with forwardly extending arms and a socket, a sleeve pivotally held between said arms, a beater rod held in the sleeve, and a spring in the socket bearing on the rod. 90

2. A device of the kind described comprising a clamp adapted to fit a drum rim, arms extending from the clamp, set screws working through said arms, a sleeve held between said screws, upwardly and downwardly extending rods held in said sleeve, a beater carried by the downwardly extending rod, a sleeve carried by the upwardly extending rod and at right angles thereto, and a cymbal beater rod carried by the last mentioned 100 sleeve.

3. A device of the kind described comprising a clamp having projecting arms, a socket and projecting guides in advance of the socket, a sleeve between the arms, set screws 105 working through the arms and engaging the sleeve, a beater rod adjustably held in the sleeve and depending between the guides,

and a spring seated in the socket and bearing on the rod.

4. A device of the kind described comprising a rim clamp, a sleeve pivotally held by said clamp, a depending beater rod carried by the sleeve, an upwardly extending rod carried by the sleeve and angled at its upper end, a split sleeve carried by the angled por-

tion of the rod, and a cymbal beater rod carried by the split sleeve, as and for the purpose set forth. 10
